UNITED STATES PATENT OFFICE.

CHARLES NEELY, OF EBENSBURG, PENNSYLVANIA.

SHINGLE-CUTTING DEVICE.

1,146,089.

Specification of Letters Patent. Patented July 13, 1915.

Application filed April 7, 1915. Serial No. 19,738.

To all whom it may concern:

Be it known that I, CHARLES NEELY, a citizen of the United States, residing at Ebensburg, in the county of Cambria and State of Pennsylvania, have invented certain new and useful Improvements in Shingle-Cutting Devices, of which the following is a specification, reference being had to the accompanying drawings.

This invention relates to an improved shingle cutting device of that character shown and described in Patent No. 1,092,381, issued to me April 7, 1914.

The present invention has for its primary object to generally simplify and improve the construction of my original invention, whereby asbestos shingles may be expeditiously and accurately cut without danger of breaking or mutilating the same so as to render them unfit for use.

It is a more specific object of my invention to provide an improved construction and mounting of the movable knife blade whereby a shearing cut upon the material at the necessary pressure may be obtained with a minimum of manual labor.

It is an additional object of the invention to produce a cutting device for asbestos shingles which is highly durable as well as very efficient and reliable in practical operation and may be produced at comparatively small manufacturing cost.

With the above and other objects in view, my invention consists in the novel features of construction, combination, and arrangement of parts to be hereinafter more fully described, claimed, and illustrated in the accompanying drawing, in which,

Figure 1 is a perspective view illustrating the preferred embodiment of the present invention; Fig. 2 is a transverse section of the device; and Fig. 3 is a section taken on the line 3—3 of Fig. 2.

Referring in detail to the drawing, 5 designates the base or body bar of the device, the opposite ends of which are bolted or otherwise rigidly fixed upon the blocks or cleats 6. Each of these end blocks is provided with a standard consisting of 10 the spaced vertical arms 7 between which one end of the vertically movable cutter bar 8 is engaged. Upon one face of this bar, the longitudinally extending cutting blade 9 is secured by a series of screws indicated at 10. This cutting blade tapers lon-

gitudinally from one of its ends to the other and the cutting edge thereof, indicated at 11, is disposed below the plane of the lower edge of the bar 8. This cutting edge of the blade 9 is very slightly inclined or beveled transversely, and it is in this slight inclination of the cutting edge of the blade that the practical effectiveness of the cutting action resides. To the opposed longitudinal edge of the base or body bar 5, a metal strip 12 is secured, with the upper edge of which the cutting edge 11 of the blade 9 co-acts.

To the opposite ends of the vertically movable bar 8 and upon the upper edge thereof, the lugs or ears 13 are secured. A lever 14 is fulcrumed at one of its ends upon a transverse bolt 15 which is mounted in the upper ends of the spaced vertical arms 7 on one of the end blocks 6. The other end of this lever 14 is provided with a longitudinally extending slot 16. A relatively long lever 17 is fulcrumed at one end upon a bolt 18 secured in the upper ends of the arms 7 on the other of the end blocks 6. This latter lever, intermediate of its ends, carries a bolt 19, preferably provided with an anti-friction roller which is slidably engaged in the slot 16 of the lever 14. Spaced links 20 connect each of the levers 14 and 17 adjacent its pivoted end, to one of the ears 13 on the cutter bar. A rubber cushioning disk, indicated at 15', for the lever 17 is arranged upon the end of the bolt 15.

It is to be particularly observed, from reference to Fig. 2 of the drawing, that the cutting edge 11 of the knife blade 9 is slightly spaced laterally from the edge of the metal strip 12 which is secured to the base 5 so that they will not contact with each other in the operation of the device.

In the operation of the machine, the asbestos composition shingle is laid upon the base 5, the asbestos sheet projecting over the upper edge of the plate 12 and beneath the cutting edge of the blade 9. The operator now forces downwardly upon the free end of the lever 17 which is formed with a suitable handle and thus also forces the free end of the lever 14 downwardly. The bar 8, carrying the cutter blade, is thus lowered so that the cutting edge of the blade will engage upon the asbestos sheet. As this cutting edge will first contact at one end of the blade with the surface of the asbestos sheet, it will be manifest that, upon a continued

downward pressure, there will be a shearing cutting action of the knife blade through the sheet of asbestos.

The base 5 of the device is provided with 5 a suitable gage indicated generally by the numeral 21. As this gage is fully shown and described in my prior patent, above referred to, the same will not, therefore, be set forth in detail in the present specification. It will suffice to state that, by simply 10 adjusting the movable gage bar to the proper position, shingles of any desired dimensions may be quickly and accurately cut.

From the foregoing description, taken in 15 connection with the accompanying drawing, the construction, manner of operation, and several advantages of my invention will be apparent. It will be seen that I have materially simplified and improved the construction of my prior invention, whereby the same is rendered more positive and reliable 20 in its action. The device may be operated with a minimum of labor upon the part of the operator to quickly cut a large number 25 of shingles. It is apparent, of course, that the body bar which carries the movable cutting blade may be of any desired cross-sectional form as may be requisite in order that the same will have the necessary inherent 30 strength. In view of the fact that the device embodies in its construction but few parts which are all of exceedingly simple form, it will further be seen that the invention 35 can be manufactured and sold at relatively small cost.

While I have shown and described the preferred construction and arrangement of the several elements, it is to be understood that the device is susceptible of considerable 40 modification therein, and I, therefore, reserve the privilege of resorting to all such legitimate modifications as may be fairly embodied within the spirit and scope of the invention as claimed.

45 Having thus fully described my invention, what I desire to claim and secure by Letters Patent is:—

1. In a cutting device of the character described, a vertically movable cutter bar, 50 guides for the ends of said cutter bar, levers pivotally mounted at one of their ends upon said guides and connected to each other for

relative movement, one of said levers being provided with a handle, and links connected to the respective levers contiguous to their 55 pivoted ends and to the relatively opposite ends of the cutter bar.

2. A cutting device of the character described including a vertically movable cutter bar, guides for the ends of said cutter bar, 60 levers pivotally mounted at one of their ends upon the respective guides, one of said levers being provided in its free end with a longitudinal slot, a bolt fixed in the other lever for longitudinal movement in said slot, said 65 latter lever being provided with a handle, and links connected at one of their ends to the respective levers contiguous to their pivots and at their other ends to the relatively opposite ends of the cutter bar. 70

3. A cutting device for asbestos shingles including a base, a metal plate secured to one of the longitudinal edges of said base, a vertically movable cutter bar, guides upon the base in which the ends of the cutter bar are 75 movably mounted, a cutting blade fixed to one face of said bar and having its cutting edge disposed below the plane of the lower face of said bar, the cutting edge of said blade being longitudinally inclined with respect to 80 the base to effect a shearing cut, and manually operable means connected to the cutter bar to actuate the same.

4. A device for cutting asbestos shingles including a base, a metal plate secured to 85 one of the longitudinal edges of said base, a vertically movable cutter bar, guides on the base in which the ends of the cutter bar are engaged, a cutting blade secured upon one 90 face of said bar and having its cutting edge slightly inclined transversely and disposed below the plane of the lower face of said bar, said cutting edge of the blade being longitudinally inclined with respect to the base 95 to effect a shearing cut, and manually operable means mounted upon said guides and connected to the cutter bar to actuate the same.

In testimony whereof I hereunto affix my signature in the presence of two witnesses. 100
CHARLES NEELY.
